UNITED STATES PATENT OFFICE.

THOMAS MANAHAN, OF NEW YORK, N. Y.

CLOSURE FOR BAGS.

No. 890,366.

Specification of Letters Patent.

Patented June 9, 1908.

Application filed January 29, 1908. Serial No. 413,217.

To all whom it may concern:

Be it known that I, THOMAS MANAHAN, a citizen of the United States, residing at New York city, in the county of New York and State of New York, have invented new and useful Improvements in Closures for Bags, of which the following is a specification.

In bags, wrappers and the like for suspending apparel and other articles, difficulty was experienced because of the hanger or loop by which the bag was suspended being wrenching or wedged off by the single continuous tube employed for locking the closing flap in shut position.

By means of this invention such difficulties are avoided and the hanger and bag are both allowed to come to vertical position or into alignment and wrenching or wedging is avoided.

This invention is set forth in the following specification and claims and illustrated in the annexed drawing in which

Figure 1 is a rear elevation of a bag embodying this invention. Fig. 2 is a section along line *x* *x* Fig. 1. Fig. 3 is a perspective view of the tube. Fig. 4 is a section along line *y* *y* Fig. 3.

The bag or wrapper *a* with closing flap *b* and locking or closing tube *c* are well known. This tube being split can be slipped onto and off the bag freeing the closing flap.

The hanger or loop *d* hinges or swings on plate *e* as usual. In former devices this hanger *d* pressing against the closing tube *c* when the bag is suspended would be liable to be wrenching or wedged off or the plate *e* with the clothes hooks *g* would be torn from the bag. By providing tube *c* with a cut-out *f*, the loop or hanger *d* is allowed to swing in a vertical position or into line with the bag, avoiding the prying process of the continuous tube.

The bag with the contents then being suspended, the pull on the hanger *d* as well as on hooks *g* being vertically downward will not tend to wrench the hanger *d* off its hinge or off the bag, since there will be no leverage on the hanger due to contact with the tube.

The hooks *g* are secured through slots in the plate *e* as heretofore. In addition to the plate *e* a re-inforcing plate *h* through which the hooks *g* are passed and clenched give additional hold so that the hooks *g* can support the weight of heavy garments or other material suspended in the bag.

In order to prevent the tube catching as it is slipped into place or removed said tube at the ends of its slit is beveled or rounded so as to slip past any projection in its path. The ends of the slit at the cut *f* are also beveled or rounded to allow easy passage of the tube.

In order to remove the tube of Fig. 1 the loop *d* is first turned down to lie flat against the bag. The tube thus being released by the loop *d* having been swung out of cut *f* the tube *c* can be removed from the bag.

I claim—

1. In combination, a bag; a removable split-tube provided with a cut-out in its side, said tube being adapted to be inserted endwise on the bag straddling the sides thereof at its mouth; and a metal suspension-hanger pivotally secured to a ply of the bag and adapted to be pivoted into and out of the cut-out in the side of the tube when said tube is on the bag, said cut-out being adapted in depth to receive the hanger without substantial leverage thereon due to contact with the tube when the hanger is in the cut-out and is suspending the bag.

2. In combination, a bag; a removable split-tube provided with a cut-out, said tube being adapted to be inserted endwise on the bag straddling the sides thereof at its mouth; and a bag-suspending hanger secured to the bag and movable into and out of the cut-out in the tube, when said tube is on the bag, said hanger when located in the cut-out having its free end substantially central over the top of the tube.

3. In combination, a bag; a removable split-tube provided with a cut-out, said tube being adapted to be inserted on the bag straddling the sides thereof at its mouth; a pair of plates on opposite sides of one ply of the bag near its mouth, secured together through said ply; and a suspension hanger secured to the outside plate receivable into the cut-out in the tube above which its free end is adapted to project to suspend the bag; and an article-supporting device on the inside plate within the bag.

In testimony whereof I have hereunto set my hand in the presence of two subscribing witnesses.

THOMAS MANAHAN.
